Patented Jan'y 21. 1851. - Jagger Treadwell & Perry. inventors

Des. 346

Ha Jagger, Samuel W. Gibbs, of Albany, N. Y. Assign to
Setters Patent No. 246 dated Jan. 21, 1854, aforesaid.

The Schedule referred to in these Setters Patent, and making part of the same.

To all whom it may concern,

Be it known, that I, Samuel W. Gibbs of the City of Albany and State of New York, have produced a new ornamental Design for a Cooking Stove, which Stove, so ornamented, is called Monarch Air tight, and I declare the annexed and accompanying drawing to be a full and accurate delineation of the same.

What I claim as my production and desire to secure by Setters Patent, is the Combination & arrangement of ornamental figures and forms represented in the annexed drawings, as making an ornamental design for a Cooking Stove.
